UNITED STATES PATENT OFFICE

117,138

DESIGN FOR A BOTTLE OR SIMILAR ARTICLE

John D. Buckingham, Chicago, Ill., assignor to Lucien LeLong, Inc., Chicago, Ill., a corporation of Illinois

Application January 19, 1939, Serial No. 82,435

Term of patent 7 years

To all whom it may concern:

Be it known that I, John D. Buckingham, a citizen of the United States and a resident of the city of Chicago, in the county of Cook and State of Illinois, have invented a new, original, and ornamental Design for a Bottle or similar article, of which the following is a specification, reference being had to the accompanying drawing, forming a part thereof.

I claim:

The ornamental design for a bottle or similar article, as shown.

JOHN D. BUCKINGHAM.
